(57) **CLAIM**

The ornamental design for the trim for a recessed luminaire, as shown and described.

DESCRIPTION

FIG. 1 is a top perspective view of a trim for a recessed luminaire, showing our new design;

FIG. 2 is a bottom perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left-side elevation view thereof; and,

FIG. 8 is a right-side elevation view thereof.

The broken lines (where present) in all FIGS. illustrate portions of the trim for a recessed luminaire that form no part of the claimed design.

1 Claim, 6 Drawing Sheets
